CLAIM

(58) **Field of Classification Search** D8/70;

I claim the ornamental design for an accessory interface for a tool, as shown and described.

D15/140; 30/166.3, 169, 272.1, 277.4, 294,
30/339, 347, 389, 392; 83/665, 666, 676,
83/835, 886; 125/15, 25, 13.01; 403/3, 316,
403/359.3, 163; 451/8, 28, 57, 163, 294,
451/342, 344, 349, 353, 356, 357, 359, 360,
451/41, 490, 494, 508, 509, 510, 511, 548,
451/559

DESCRIPTION

See application file for complete search history.

FIG. 1 is a perspective view of an accessory interface.
FIG. 2 is a front view of the accessory interface shown in FIG. 1.

FIG. 3 is a top view of the accessory interface shown in FIG. 1.

FIG. 4 is a bottom view of the accessory interface shown in FIG. 1.

FIG. 5 is a left side view of the accessory interface shown in FIG. 1; and,

FIG. 6 is a right side view of the accessory interface shown in FIG. 1.

The broken line showing of the environment is for illustrative purposes only and forms no part of the claimed design. The broken lines having unequal length segments define the boundaries of the claimed design and form no part thereof.
